UNITED STATES PATENT OFFICE.

HARADEN PRATT, OF SAN FRANCISCO, CALIFORNIA.

RADIOTELEGRAPHIC RECEIVING SYSTEM.

1,367,165.

Specification of Letters Patent.

Patented Feb. 1, 1921.

Application filed July 21, 1919. Serial No. 312,454.

To all whom it may concern:

Be it known that I, HARADEN PRATT, a citizen of the United States, and an employee of the Navy Department, residing at 5 1510 Lombard street, city and county of San Francisco, California, (whose post-office address is Bureau of Steam Engineering, Navy Department, Washington, D. C.,) have invented an Improvement in Radiotelegraphic Receiving Systems, of which the following is a specification.

My invention relates broadly to an improvement in radiotelegraphic communication and more particularly to a new method 15 for the reception of radiotelegraphic signals and has for its object the production of useful mechanical vibrations directly through the magnetic action of radio frequency currents.

20 The currents induced in radio receiving systems are ordinarily of too high a frequency to enable them to produce useful direct mechanical movements; but the tendency of the art during recent years has been 25 toward lower frequencies, so that at the present day, frequencies are being employed for long distance communication which are sufficiently low to enable them to produce mechanical motions directly. Certain radiotelegraphic stations have been in continuous 30 operation for trans-Atlantic communication for over ten months past, which have been regularly employing radio frequency currents between 17,000 and 20,000 cycles per 35 second. Tuning forks and other mechanical and acoustic apparatus utilizing frequencies of this order have been well known in the sciences for some time past and this invention pertains to means for generating 40 useful and intelligible mechanical vibrations directly obtained from currents of such frequencies.

In order to more clearly illustrate my invention, I shall describe an embodiment 45 thereof in connection with the annexed drawing.

In a radiotelegraphic receiving system, a source of radio frequency potential is supplied by antenna 1, in circuit with condenser 2, inductance 3 and earth connection 4. The inductance has terminals 5 and 6 connected to the input of radio frequency amplifier 7 and transferred through transformer 9, by means of primary winding 8 and secondary 55 10 to an electrically tuned circuit containing condenser 11 and an electromagnet 13 hav-

ing a winding 12. Associated with this electromagnet is a mechanically tuned armature 14 of steel, permanently magnetized, and so related in position that one of its magnetic 60 poles may be acted upon magnetically by the electromagnet. An alternating radio frequency current flowing in the electromagnet 12 produces a magnetic field at the end of its core which is also alternating thereby causing 65 vibrations of the magnetically polarized mechanically tuned armature, which are made possible through the spring action of the armature as the latter is fastened rigidly to a fixed base 15, with its upper end free to 70 vibrate. The mechanical tune of the armature must be such that its vibrations will be in synchronism with the radio frequency current used. This mechanical vibration may be damped by any suitable means, 75 such as immersing the armature in a fluid, so that such vibration will not continue after the flow of radio frequency current in the electromagnet has ceased. If this armature is arranged for tracing an inked record 80 upon a moving cylinder 17 advanced by screw 18, the radio telegraphic signals may be received and recorded thereon in a legible manner by means of pen 16 from the groups of radio frequency currents generated in the 85 system.

Although I have specified above a particular application, my invention is by no means limited thereto, but applies as well to any source of radio frequency current in 90 a radiotelegraphic receiving system associated with a mechanical recorder with or without the use of radio frequency transformers wherein the recorder derives energy directly from such current for producing 95 useful mechanical vibrations suitable for rendering intelligible, radiotelegraphic signals impinging thereon.

What I claim and desire to secure by Letters Patent is:

100 In a radiotelegraphic receiving system the combination of a source of radio frequency current with a tuned circuit containing an electromagnet having an armature mechanically tuned and adapted to vibrate mechanically in synchronism with said radio frequency current, and means for making such vibrations useful for the intelligible reception of radio telegraphic characters substantially as described.

HARADEN PRATT.
